DISPENSER TOP OR SIMILAR ARTICLE FOR A
PRESSURIZED CAN

Saul Birsan, 48-20 39th St., Long Island City, N.Y.
11105; Philip M. Prussak, 44 62nd St., West New York, N.J. 07093; and Allan M. Sheldon, 2330 Voorhies Ave., Brooklyn, N.Y. 11235

Filed Apr. 25, 1966, Ser. No. 2,022

Term of patent 14 years

(Cl. D58—26)

FIG. 1.

FIG. 2.

FIG. 3.

FIG. 4.

FIG. 5.

FIG. 6.

FIG. 1 is a left front perspective view of a dispenser top showing our new design;

FIG. 2 is a front elevational view;

FIG. 3 is a right side elevational view;

FIG. 4 is a rear elevational view;

FIG. 5 is a top plan view; and

FIG. 6 is a bottom plan view.

The upper portion of a pressurized can is shown in broken lines in FIG. 3 for purposes of illustration only.

We claim:

The ornamental design for a dispenser top or similar article for a pressurized can, substantially as shown and described.
